OR D 11,536

No. 11,536

DEC 2, 1879

UNITED STATES PATENT OFFICE.

CHARLES C. DELHOMMER, OF BREAUX BRIDGE, LOUISIANA.

DESIGN FOR WATER-COOLERS.

Specification forming part of Design No. **11,536**, dated December 2, 1879; application filed October 15, 1879.
[Term of patent 14 years.]

To all whom it may concern:

Be it known that I, CHARLES CHRISTOPHER DELHOMMER, of Breaux Bridge, in the parish of St. Martin and State of Louisiana, have invented a new and Improved Design for a Water-Cooler, of which the following is a specification.

The nature of my design is fully represented in the accompanying photographic illustration, to which reference is made.

The object of this invention is to furnish a design for water-coolers especially intended for use on passenger vessels, which design shall be ornamental, and at the same time will show exactly how a life-preserved should be put on and worn, so that in case of accident the passengers will know how life-preserveds should be used, and loss of life from the improper adjustment of life-preserveds may be prevented.

A represents the water-cooler, which is made in the form of a bust provided with arms. The bust is represented as wearing a life-pre-

server, B. One arm, C, of the bust is represented as being raised into a horizontal position and bent forward, with the hand grasping the device D, by means of which the life-preserved is inflated. The other arm, E, extends downward, and the hand grasps the faucet F of the water-cooler, which faucet is represented as a rope, with a stop-cock near its outer end.

Having thus described my invention, I claim as new and desire to secure by Letters Patent—

A design for a water-cooler in which the cooler is made in the form of a bust of a human figure wearing a life-preserved, and having one of its hands grasping the inflating device of the life-preserved and the other the faucet of the cooler, substantially as herein shown and described.

CHS. CHRISTOPHER DELHOMMER.
